(57) **CLAIM**

The ornamental design for a display screen or portion thereof with a graphical user interface, as shown and described.

DESCRIPTION

The FIGURE is a front view of a display screen or portion thereof with a graphical user interface.

The outermost broken line rectangle illustrates a display screen or portion thereof. The remainder of the broken lines illustrate portions of the graphical user interface. The broken lines form no part of the claimed design.

1 Claim, 1 Drawing Sheet
